(57) **CLAIM**

The ornamental design for a nail dust collector, as shown and described.

DESCRIPTION

FIG. 1 is a first perspective view of a nail dust collector showing my new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of the selected portion 9 in FIG. 5.

The dash-dash broken lines shown in the drawings depict portions of the nail dust collector that form no part of the claimed design. The dot-dash broken lines in FIGS. 5 and 9 illustrate the boundaries of the enlarged detail view and form no part of the claimed design.
